UNITED STATES PATENT OFFICE

DAVID W. R. MORGAN, OF SWARTHMORE, PENNSYLVANIA, ASSIGNOR TO WESTINGHOUSE ELECTRIC & MANUFACTURING COMPANY, A CORPORATION OF PENNSYLVANIA

CONDENSER

Application filed October 3, 1928. Serial No. 309,989.

My invention relates to surface condensers, and more particularly to radial flow condensers, and it has for an object, to improve the performance of apparatus of this character.

This application is a continuation in part of my copending application Serial No. 219,473, filed September 14, 1927.

In the operation of surface condensers, relatively, only a very small quantity of air and other noncondensable gases pass into a condenser, but the progressive removal of the condensable gases leaves an ever increasing proportion of non-condensable gases in the gaseous media, with the result that, toward the completion of the process of condensation, the effect of the non-condensable gases upon the vacuum obtainable becomes quite appreciable.

Condensation leaves the non-condensable gases on the condensing surface where, due to their low heat conductivity, they tend to form an insulating medium and thus, to delay condensation and to retard the vapor flow.

Also, in accordance with Dalton's law of partial pressures, the total pressure in a condenser is the steam pressure plus the partial pressures due to the air and the other non-condensable gases, hence the total pressure can be maintained at a minimum value if means are provided for assuring that air and other non-condensable gases will be promptly removed from the condensing portion of the apparatus. It is desirable, therefore, to maintain a constant, relatively high velocity of vapor flow through a nest of condensing tubes in order to assure that the non-condensable gases will be brushed away from the condensing surface and promptly carried out of the condensing portion of the apparatus. It is also desirable to cool the non-condensable gases so far as possible, previous to their removal by the removal apparatus, in order to reduce the amount of work which must be done to effect their removal.

Further, in cases where divided water boxes are provided for the purpose of permitting some of the condensing tubes to be cut out of the circulating system, so that they may be cleaned or otherwise repaired during

periods of light load without shutting down the entire condenser, the conditions of temperature and pressure on the inactive side of the nest may build up to an objectionable value. If some means, other than the active side of the nest, are provided for condensing part of the steam on the inactive side of the nest, the performance of such condensers during cleaning periods, or the like may be considerably improved.

More particularly, therefore, an object of my invention is to provide means for assisting in maintaining proper vapor flow through a condenser of the type described, and to provide means, other than the active side of a nest of tubes, for reducing the temperature and pressure on the inactive side of the nest of a condenser of the divided water box type during periods when only a part of the condensing tubes are effective.

Apparatus embodying the features of my invention is shown in the accompanying drawings, in which:

Fig. 1 is a longitudinal section along the line I—I of Fig. 2 showing a surface condenser with the tubes removed;

Fig. 2 is a transverse half section on the line II—II of the condenser shown in Fig. 1 showing the tube arrangement;

Fig. 3 is a section on the line III—III of Fig. 1;

Fig. 4 is a transverse section through the inlet water box on the line IV—IV of Fig. 1;

Fig. 5 is a detail view taken on the line V—V of Fig. 2, and

Fig. 6 is an enlarged partial view, in transverse section, of the upper end of the longitudinal partition structure provided in the condenser shell.

According to my invention, the nest of tubes in a surface condenser is divided longitudinally by a partition into separate condensing portions, and a lower portion of the nest is separated from the respective condensing portions by transversely-extending roof plates to form cooling sections for cooling air and non-condensable gases passing from the respective condensing portions. Suitable entraining means, preferably one or more ejectors, are provided for entraining gaseous

media from the respective condensing portions, and these ejectors are arranged to discharge into the respective cooling sections, so that the normal flow of gaseous media from the condensing tubes to the cooling tubes may be assisted. The entraining fluid for the ejectors, or the like, may be obtained from any suitable source, as from one of the lower stages of a turbine, but preferably the ejectors are so disposed that motive fluid directly from the condenser inlet may be employed as the entraining medium and thus, it is possible to use motive fluid direct from the last row of turbine blades, and to utilize the velocity of this motive fluid in the operation of the ejectors.

The water boxes for the condenser are also divided vertically and transversely so that the flow of circulating media through the respective condensing and cooling portions of the condenser may be selectively controlled. In this way, it is possible to pass circulating media through both cooler sections while one side of the condenser proper is shut down and thus, to provide active cooling surface for gaseous media which enters the inactive side at a time when this cooling surface is most needed.

Referring now to the drawings for a better understanding of my invention, I show a radial flow, surface condenser indicated generally at 10, comprising a shell 11, having a motive fluid exhaust inlet 12 and provided with a hot well 13. A nest of water tubes 14 is disposed within the shell 11 and the lower portion of the nest 14 is divided longitudinally by suitable partition means 16 so as to provide separate condensing chambers. The lower portion of the nest 14 is separated by transversely-extending, arched roof plates 17, which are secured to the shell and arranged to form a crowned roof for the cooler sections 18 and 19, respectively.

The partition means 16 preferably extend from the base of the shell through the cooler sections and the roof plates 17 well into the condensing portion of the nest 14. In the form shown, this partition means comprises a longitudinally-extending plate 21, which is disposed substantially upon the vertical center line of the nest 14, and spaced from the plate 21 on either side is a plate 22, which extends from the roof plate 17 to a height corresponding substantially to that of the plate 21, so as to form a passage on either side of the plate 21 to the respective cooler sections 18 and 19. The plates 22 are provided with a plurality of openings 23 disposed just above the roof plates 17 for the purpose of passing air and other noncondensable gases from the respective condensing portions to the respective cooling portions 18 and 19.

While the partition means 16 does not extend vertically to the uppermost portion of

the tube nest 14, the tubes in the upper portion are spaced so as to provide a steam lane 23', which affords direct communication from the condenser inlet to the passages 24, which are formed by the plates 21 and 22, so that motive fluid may pass directly from the condenser inlet to the respective cooling chambers, and in passing the openings 23 in the plates 22, gaseous media from the condensing chambers may be entrained, and the flow from the condensing chambers to the cooling chambers thereby assisted. Suitable baffles 25 are disposed above the ports 23, to protect the latter from the rain of condensate.

While this means may be sufficient to produce adequate flow in many cases, I preferably arrange suitable fluid translating means, such as the ejectors 26 in each of the passages 24 adjacent the openings 23, in order that gaseous media may be entrained by the ejectors and discharged into the respective cooling chambers, so as to insure that proper flow from the condensing chambers through the openings 23 and the passage 24 to the cooling chambers may be maintained at all times.

When the ejectors 26 are used, the passages 24 are closed at their upper ends by a transversely-extending baffle 27, which is provided with suitable openings 30 so spaced longitudinally as to pass motive fluid through the baffle 27 and respective tubes 28 to the jet of each ejector. In this way the motive fluid exhaust direct from the condensing inlet is utilized as the entraining medium for the respective ejectors and thus, advantage is taken of the high velocity of the motive fluid from the last row of turbine blades. Should it be desirable, however, these ejectors may be supplied with entraining medium from any other source, as from a lower stage of a turbine.

The ejectors 26 are preferably arranged to have a progressively decreasing capacity from the circulating fluid inlet to the discharge end of the tube nest, as shown. Hence, as shown in Fig. 5, the openings 30 for admitting motive fluid to the respective ejectors preferably decrease in size in a direction from the inlet water box 40 toward the discharge water box 53. This is desirable in order to compensate for the progressive rise in temperature of the circulating media as it passes through the tubes. While this feature of my invention is intended more for a single-pass condenser, it will be understood that it is not so limited in its application, but that it may be used on multi-pass condensers.

Gaseous media, such as air and the like, which passes into the respective cooler sections 18 or 19, is cooled by tubes of these portions and is removed through removal ports 29 by any suitable air removal apparatus (not shown). The hotwell 13 receives condensate from the condensing chambers through the connections 31, which communicate with the

steam space between the tubes 14 and the shell 11 and are arranged to receive condensate passing through the steam space and also the condensate which drains off the roof plates 17. By passing the condensate through the steam space in this way, its temperature is raised and consequently less heating is required when it is used for boiler feed purposes.

10 The condensate which passes through the connections 31 to the hotwell 13, passes over an upstanding wall 32 within the hotwell so as to provide a liquid seal between the condensing tubes 14 and the collection chamber 33 of the hotwell. Similarly, the brim, or upper portion of the cup 34, is arranged to encompass the lower portion of the connection 36 so as to provide a liquid seal between the respective cooling sections 18 and 19 and 20 the collection chamber 33 of the hotwell.

One or more vents 37 are provided for maintaining a pressure in the collection chamber 33 corresponding to that in the cooling portions 18 and 19 so that deaeration 25 may take place within the hotwell. The hotwell 13 is described and claimed in my former Patent, No. 1,578,058, and therefore is only briefly referred to here.

In order to provide for selectively controlling the flow of circulating media through the respective cooling and condensing chambers, the inlet water box 40, is divided by a longitudinally-extending vertical partition 41 to provide separate inlet portions 42 and 43, which are provided with suitable inlets 44, through which the flow of circulating media is controlled by any suitable means, such as the valves 46. Similarly, the water box is divided transversely by an arched partition 47 to provide, with the partition 41, separate inlet chambers 48 and 49, which are also provided with inlets 50 through which the flow of circulating media is controlled by suitable valves 51. The respective chambers 48 and 49, supply circulating media for the cooling tubes in the cooling chambers 18 and 19, respectively. It will readily be seen therefore that by regulating the valves 51, the flow through the respective cooler sections of the condenser may be controlled.

The discharge water box 53, is similar in all respects to the inlet water box 40, with the exception that circulating media from the condensing portions of the nest is discharged through connections 54 near the top of the water box. The circulating water from the respective cooler sections is discharged through the outlets 55.

60 It will be obvious that the ejectors 26 and the baffles 27 may be omitted, in which case live steam from the condenser inlet would pass down the lane 23, between the plates 21 and 22 to the cooling sections 18 and 19. In 65 so passing, this steam would entrain gaseous

media through the ports 23 and carry the entrained media into the respective cooling sections, and thus assist the flow through the condensing portions of the nest 14.

It will readily be seen, therefore, that I 70 have provided a condenser embodying simple and efficient means for assisting the flow of gaseous media from the condensing portions to the cooling portions. Also, the cooling portions of the nest are selectively controllable 75 so that steam from a side of the nest, which has been cut off from the circulating system, may be cooled at a time when cooling is most needed.

While I have shown my invention in one 80 form, it will be obvious to those skilled in the art that it is not so limited, but is susceptible of various changes and modifications, without departing from the spirit thereof, and I desire, therefore, that only such limitations shall be placed thereupon as are imposed by the prior art or as are specifically set forth in the appended claims.

What I claim is:

1. A surface condenser comprising a shell 90 having an inlet, a nest of tubes within the shell, means for separating the tubes into a plurality of condensing compartments and into a like number of cooling compartments, and means for assisting the flow of gaseous 95 media from each condensing compartment to a cooling compartment.

2. A surface condenser comprising a shell 100 having an inlet, a nest of tubes within the shell, means for separating the tubes into a plurality of condensing compartments and into a like number of cooling compartments, and means within the nest for assisting the flow of gaseous media from each condensing compartment to a cooling compartment.

3. A surface condenser comprising a shell 110 having an inlet, a nest of tubes within the shell, means for separating the tubes into a plurality of condensing compartments and into a like number of cooling compartments, fluid entraining means for assisting the flow of gaseous media from each condensing compartment to a cooling compartment, and means for passing gaseous media directly 115 from the condenser inlet to the entraining means.

4. The combination with a surface condenser comprising a shell having an inlet, a nest of tubes within the shell and spaced therefrom to provide a steam delivery space substantially around the nest, and a condensate removal connection communicating with the steam delivery space, of partition means for dividing the nest into a condensing portion and a cooling portion, said partition means being inclined gradually toward the condensate removal connection.

5. The combination with a surface condenser comprising a shell having an inlet, a nest of tubes within the shell, means for

separating the tubes into a plurality of condensing compartments and into a like number of cooling compartments, means providing a passage from the condenser inlet to each of the respective cooling compartments, and means for affording communication between the respective condensing compartments and the passage.

6. A surface condenser comprising a shell having an inlet, a nest of tubes within the shell, a partition extending longitudinally through the nest of tubes, arched roof members extending transversely through the nest of tubes and secured to the shell and to the partition for dividing the nest into an upper condensing portion and a lower cooling portion, said partitions being arranged for passing gaseous media from the condensing portion to the cooling portion, and means within the partition for assisting the flow of gaseous media from the condensing portion to the cooling portion.

7. A surface condenser comprising a shell having an inlet, a nest of tubes within the shell, arched roof members extending transversely through the nest of tubes and secured to the shell for dividing the nest into an upper condensing portion and a lower cooling portion, and means for entraining gaseous media from the condensing portion and for discharging the entrained media into the cooling portion.

8. A surface condenser comprising a shell having an inlet, a nest of tubes within the shell and spaced therefrom to provide a steam delivery space substantially around the nest of tubes, condensate removal connections communicating with the steam delivery space, arched roof members extending transversely through the nest of tubes and dividing the nest into an upper condensing portion and a lower cooling portion, the arched roof members being arranged to drain to the condensate removal connections, whereby condensate passing from the roof members may be heated by steam from the steam delivery space.

9. A surface condenser comprising a shell having an inlet, a nest of tubes within the shell, curved members extending transversely through the nest of tubes for dividing the nest into an upper condensing portion and a lower cooling portion, the curved members being arranged to form a crowned roof for the cooling portion, condensate removal connections in communication with a steam delivery space and arranged to receive condensate from the crowned roof and from tubes in the condensing portion.

10. A surface condenser comprising a condensing chamber and a cooling chamber, said chambers having respective inlet and outlet connections, and being arranged for passing gaseous media therethrough in series, a number of tubes traversing each chamber and

means for passing gaseous media directly from the inlet of the condensing chamber to the inlet of the cooling chamber, whereby the passage of gaseous media from the condensing chamber to the cooling chamber may be assisted.

11. A surface condenser comprising a shell, partition means separating the shell into a condensing chamber and a cooling chamber, heat transfer tubes traversing each chamber, means providing a passage from the condensing chamber to the cooling chamber, and a plurality of ejectors in said passage and spaced apart lengthwise of said tubes, said ejectors being of decreasing capacity in the direction of flow of circulating media through said tubes.

12. The combination with a surface condenser embodying a shell structure having inlet means for gaseous media and outlet means for condensate and non-condensable gaseous media spaced from the inlet means and a tube nest extending longitudinally through the shell structure, of fluid translating means disposed within the shell structure for facilitating the circulation of gaseous media from the inlet means through the tube nest to the outlet means.

13. The combination with a surface condenser embodying a shell structure having inlet means for gaseous media and outlet means for condensate and non-condensable gaseous media spaced from the inlet means and a tube nest extending longitudinally through the shell structure, of entraining means motivated by gaseous media derived directly from the condenser inlet means for facilitating the circulation of gaseous media from the inlet means through the tube nest to the outlet means.

14. A surface condenser embodying an inlet for media having condensable and non-condensable components, separate outlets for the condensed media and the non-condensed media, and fluid translating means provided in the condenser for facilitating the passage of the non-condensable media through the condenser from the inlet to the non-condensable gaseous media outlet.

15. A surface condenser embodying an inlet for media having condensable and non-condensable components, separate outlets for the condensed media and the non-condensed media, and an ejector disposed in the condenser for facilitating the passage of the non-condensable gaseous media through the condenser from the inlet to the non-condensable media outlet, said ejector being motivated by the gaseous media passing through the inlet.

16. A surface condenser embodying an inlet for gaseous media having both condensable and non-condensable components, a tube nest divided into a condensing portion and a cooling portion, condensate outlet

means connecting with the condensing portion, non-condensable gaseous media outlet means communicating with the cooling portion, and fluid translating means for facilitating movement of the non-condensable gaseous media through the condensing portion of the tube nest to the cooling portion of the tube nest.

17. A surface condenser embodying an inlet for gaseous media having both condensable and non-condensable components, a tube nest divided into a condensing portion and a cooling portion, condensate outlet means connecting with the condensing portion, non-condensable gaseous media outlet means communicating with the cooling portion, and entrainment means motivated by gaseous media derived from the inlet for facilitating circulation of the non-condensable gaseous media through the condensing portion of the tube nest to the cooling portion of the tube nest.

18. A surface condenser embodying an inlet for gaseous media having both condensable and non-condensable components, a tube nest divided into a condensing portion and a cooling portion, condensate outlet means connecting with the condensing portion, non-condensable gaseous media outlet means communicating with the cooling portion, and fluid translating apparatus for scavenging the condensable portion of the tube nest of non-condensable gaseous media and for discharging the same to the cooling portion of the tube nest.

19. A surface condenser comprising a shell structure having an inlet for gaseous media and outlet means for condensate and non-condensable gaseous media, a tube nest extending longitudinally through the shell structure, a water box disposed at each end of the tube nest and providing for the circulation of cooling water in a single, longitudinal direction through the tube nest, and fluid translating means extending longitudinally within the shell structure for facilitating the circulation of gaseous media through the tube nest, said fluid translating means having a decreasing capacity in the direction of the flow of the circulating water.

20. In a surface condenser embodying a shell structure having an inlet for gaseous media and outlet means for condensate and non-condensable gaseous media, a tube nest extending longitudinally through the shell structure, an inlet water box associated with one end of the tube nest and defining a cold end thereof, an outlet water box associated with the other end of the tube nest and defining a warm end thereof, and fluid translating means within the shell structure for facilitating the circulation of gaseous media through the tube nest, said fluid translating means having a relatively greater capacity

at the cold end of the tube nest than at the warm end of the tube nest.

In testimony whereof, I have hereunto subscribed my name this 2nd day of October, 1928.
